UNITED STATES PATENT OFFICE

2,115,442

SPRAY NOZZLE

Walter T. Emery, Manhattan, Kans.; dedicated
to the free use of the People of the United
States

Application October 28, 1937, Serial No. 171,515

2 Claims. (Cl. 299—140)

(Granted under the act of March 3, 1883, as
amended April 30, 1928; 370 O. G. 757)

This application is made under the act of
March 3, 1883, as amended by the act of April
30, 1928, and the invention herein described and
claimed, if patented, may be manufactured and
used by or for the Government of the United
States for governmental purposes without the
payment to me of any royalty thereon.

I hereby dedicate the invention herein de-
scribed to the free use of the People of the United
10 States of America to take effect on the granting
of a patent to me.

This invention relates to spray nozzles and is
more particularly concerned with a spray nozzle
adapted to utilize the exhaust gases of petro-
15 leum engines to spread a liquid insecticide into
a mist or spray.

An object of this invention is to provide an
article for the use of anyone possessing an auto-
mobile, truck, tractor, or other machine, having
20 a power plant of the types mentioned, to combat
injurious insects simply by attaching this article
to the exhaust of the power plant and to reser-
voir of a spray solution.

The following specification, taken in consider-
ation with the accompanying drawing, will fully
25 disclose this invention, and other objects and ad-
vantages thereof will be apparent.

In the drawing:

Figure 1 is a plan view of this invention.

30 Figure 2 is a cross-sectional view of Figure 1
along the line 2—2.

Figure 3 is an end elevational view.

Figure 4 is a fragmentary cross-sectional view
of Figure 3 along the line 4—4.

35 Figure 5 is a fragmentary cross-sectional view
of Figure 3 along the line 5—5.

Referring with more particularity to the draw-
ing in which like parts are designated by like
numerals, the numeral 1 designates the main
40 body portion having an expansion chamber 2
communicating with a recompression chamber 3,
substantially as shown. A flexible hose is se-
cured to the screw-threaded nipple 5 by means
of the screw-threaded cap 6. The bands 7 and
45 the washer 8 are employed to provide a tight seal
for the hose connection. The other end of said
hose 9 is adapted, by means of the bands 9, for
attachment to the exhaust pipe 10 of an engine.

Integral with said recompression chamber is
50 a tube 11 having an internal grid member 12
disposed longitudinally through said pipe and

extending exteriorly therefrom to form a wall
for the narrowed end of said recompression
chamber. A plurality of slotted sections 14 are
provided at intervals along said grid member.
Each of these slotted sections extend a short 5
distance into the interior of said tube 11, sub-
stantially as shown. One end of said tube 11 is
closed, while the other end is connected to a
pipe 15 adapted to conduct a fluid spray. Said
pipe 15 is provided with a valve 16 for regulating 10
the flow of said fluid.

The operation of this invention is as follows:
The hose member 4 is attached to the exhaust
pipe of an engine and the pipe 15 is attached to
a spray fluid reservoir. As the exhaust gases 15
from the engine pass into the expansion chamber
2 and then continue to flow into the recompre-
ssion chamber 3, they spread and produce a uni-
form pressure on the slots 14. The spray fluid
is conducted to the grid slots through the pipe 20
line 15 by any convenient method, such as gravity
flow, forced feed, etc. The suggestion is made
that the exhaust gases from the engine can be
passed through an enclosed barrel or tank con-
taining the fluid spray, thereby maintaining a 25
constant delivery pressure.

The operation of this invention has the effect
of spreading the spray fluid into a thin film
preparatory to being blown out as a spray or
30 mist.

Having thus described my invention, I claim:

1. In a spray nozzle, an expansion chamber
communicating with the exhaust gases of a pe-
troleum engine, a recompression chamber com-
35 municating with said expansion chamber, a
slotted grid section disposed as a wall of said
recompression chamber, and a spray fluid deliv-
ery tube, said grid section extending into the in-
terior of said tube.

2. An article of manufacture comprising a 40
flexible hose, one end of which is adapted to be
attached to the exhaust pipe of a petroleum en-
gine, an expansion chamber attached to the
other end of said flexible hose, a recompression
chamber attached to said expansion chamber, a 45
slotted grid section forming an outlet end wall
for said recompression chamber, and a fluid spray
delivery tube integral with said grid section and
communicable with the slots thereof.

50

WALTER T. EMERY.
